PRESSING PAD WITH ATTACHED
PRESSING CLOTH

Theresa M. McKinley, New York, and David Traum, Purchase, N. Y., assignors to Dritz-Traum Co., Inc., New York, N. Y., a corporation of New York

Application May 30, 1945, Serial No. 596,754

5 Claims. (Cl. 38—141)

1

This invention relates to garment pressing accessories and has particular reference to a pressing pad provided with a pressing cloth secured thereto along one side thereof and adapted to overlie a garment to protect the same during the pressing operation while the pad affords a support therefor.

The invention primarily comprehends a pressing pad for use in the pressing of the shoulder portions of coats, jackets and the like whereby the pad may be held in one hand by the operator under the shoulder portion of the garment and the pressing cloth folded over the edge of the garment and disposed in covering relation with the surface thereof to be pressed to thereby protect the same during the pressing operation which is performed by the operator using a heated iron in the other hand.

The invention also has in view a pressing pad of the indicated character which is formed with hand engaging means for holding the same during the pressing operation and in which the pressing cloth is secured to the pad adjacent the entrance of the hand engaging means.

The invention further comprehends a pressing cloth including upper and lower mating fabric sections secured together to provide a casing which is filled with a soft compressible fibrous material and to which casing a fabric section is secured in spanning relation with the lower section thereof to form a pocket therewith for receiving the hand of the operator and adjacent the entrance to the said pocket a flexible strip of material is secured to the end of the casing so as to define a pressing cloth.

With the foregoing and other objects in view reference is now made to the following specification and accompanying drawings in which the preferred embodiment thereof is illustrated.

In the drawings:

Fig. 1 is a side view of a pressing pad constructed in accordance with the invention and illustrating the pressing cloth disposed in superposed relation.

Fig. 2 is a sectional view therethrough on line 2—2 of Fig. 1.

Fig. 3 is a side view on a reduced scale of a pressing pad constructed in accordance with the invention and illustrating a modified form thereof.

Referring to the drawings by characters of reference, the pressing pad includes a flexible casing preferably constructed of woven fabric which casing consists of upper and lower mating plies or sections 10 and 11 which are se-

2

cured together by stitching 12 continuously about the peripheries thereof with the selvage edges of the plies or sections inturned. The casing is filled with a compressible fibrous material such as cotton wadding 13 which distends the same and provides an elongated pad with a substantially flat upper surface when compressed and oval side edges in cross-sectional configuration.

A ply or section 14 preferably of woven fabric is provided which is similar in formation to the lower ply or section 11 but of reduced length and which underlies the lower ply or section 11 and is secured to the casing so as to form a pocket therewith for receiving the hand of the operator so as to support the pad in position within the garment and under the surface to be pressed, the pocket having an entrance mouth 15 which is spaced from one end of the pad. As illustrated, the ply or section 14 has one end 10 thereof and its opposite side edges inturned between the edges of the plies 10 and 11 and secured thereto by the stitching 12 about said edges of the ply or section 14.

Constructed in this manner the pad may be 25 conveniently held by the operator with one hand and arranged in position under the portion of the garment to be pressed so as to provide a foundation or backing for the pressure of the pressing iron applied against the outer surface 30 of the garment which is performed by the operator holding the pressing iron in the other hand. In order to provide means for protecting the surface of the garment from direct contact with the pressing iron during the pressing operation, 35 a pressing cloth 16 consisting of a strip of flexible material such as woven fabric is secured to the pad continuously along the end 17 thereof adjacent the entrance mouth 15 of the pocket by a line of stitching 12'. As illustrated, one end 40 of the pressing cloth 16 is secured to the pad between the upper and lower plies or sections 10 and 11 by inserting the same therebetween, the line of stitching 12' at the end 17 of the pad securing the upper and lower plies or sections 10 and 11 and the pressing cloth 16 together in assembled relation and closing the end of the casing. The outer end of the pressing cloth 16 and the opposite side edges thereof are doubled over 45 and secured by a line of stitching 18 to provide a hemmed edge.

When the pad is in use and disposed in position within or under the portion of the garment to be pressed, the portion of the pressing cloth 50 adjacent the pad is folded over the edge of the

garment and the remainder thereof disposed in overlying relation upon the surface of the garment to be pressed to constitute a protection against direct contact of the iron with the garment and which pressing cloth may also be dampened to facilitate the pressing of the garment.

In the modified form of the invention illustrated in Fig. 3 of the drawings the pad includes a flexible casing consisting of a forward portion 19 which is similar in construction to the pad shown in the previous form of the invention. In this form however the forward portion 19 is provided with an elongated flexible extremity 20 which is of reduced thickness and is connected with the rear end of the forward portion 19. The said pad is preferably constructed of upper and lower mating plies or sections 21 and 22 extending longitudinally throughout the portions 19 and 20 thereof and which are secured together by stitching extending continuously about their peripheries similar to the stitching 12 in the previous form of the invention. The forward portion 19 of the pad is similarly provided with a ply or section 23 which underlies the lower ply or section 22 and is secured along its opposite side edges to the casing by the aforesaid stitching so as to form a pocket 24 with the lower ply 22.

A pressing cloth 25 similar to the pressing cloth 16 in the previous form of the invention is secured by stitching 26 to the forward end of the casing, the pressing cloth 25 however being relatively longer than the pressing cloth 16 in the previous form of the invention and extends throughout the entire length of the portions 19 and 20 thereof. The pressing pad in this form of the invention is adapted to be used in a manner similar to that described in the previous form of the invention but in this instance the forward portion 19 thereof is adapted to be disposed under the shoulder portion of the garment to be pressed with the flexible extremity 20 extending into and throughout the sleeve of the garment to provide a foundation or backing for the pressure of the iron upon the surface of the garment to be pressed while the pressing cloth 25 is adapted to overlie the shoulder portion and the sleeve of the garment so as to protect the garment from direct contact with the iron.

What is claimed is:

The casing of the pressing pad illustrated in Figs. 1 and 2 of the drawings is produced by sewing the plies 10, 11 and 14 together by the line of stitching 12 with the said plies arranged inside out after which the plies are turned right side out and the casing filled with the wadding 13 and the end 17 thereof closed by the line of stitching 12' and uniting the pressing cloth 16 thereto. In a similar manner the casing of the pressing pad illustrated in Fig. 3 of the drawings is produced.

1. In a pressing pad, an elongated casing of greater width and length than of thickness and of oval formation in cross-sectional configuration, a filling material contained in said casing and providing a pressing pad, means secured to said casing in spanning relation to and underlying the underside thereof for receiving the hand for supporting the pad in position and a flexible strip of single ply fabric connected at one end thereof to said casing adjacent the entrance of the hand receiving means and with the remaining side and end edges free and unsecured and providing a pressing cloth of a length and width to extend longitudinally and transversely over the upper surface of the pressing pad for overlying

and protecting the surface of a garment during the pressing operation with the pad supported beneath the garment and adapted to withstand the pressure of the pressing iron against the upper surface of the pressing cloth.

2. In a pressing pad, an elongated casing of greater width and length than of thickness, a filling material contained in said casing and providing a pressing pad, means secured to said casing in spanning relation to and underlying the underside thereof for receiving the hand for supporting the pad in position and a flexible strip of fabric connected at one end thereof to said casing adjacent the entrance of the hand receiving means and with the remaining side and end edges free and unsecured and providing a pressing cloth of a length and width to extend longitudinally and transversely over the upper surface thereof and to project outwardly beyond the opposite sides and one end thereof for overlying and protecting the surface of a garment during the pressing operation with the pad supported beneath the garment and adapted to withstand the pressure of the pressing iron against the upper surface of the pressing cloth.

3. In a pressing pad, a casing having a relatively broader upper surface than thickness thereof and including upper and lower mating fabric sections, stitching securing said sections together about their peripheries, a filling material in said casing and forming the same into a pressing pad, a fabric section underlying said casing and being secured between said mating fabric sections by said stitching to define a pocket with said casing for receiving the hand of the operator and a flexible strip of single ply material defining a pressing cloth secured at one end thereof only to said casing by said stitching adjacent the entrance to said pocket and said pressing cloth being of a length and width to extend longitudinally and transversely over the upper surface of the pressing pad for overlying and protecting the surface of a garment during the pressing operation with the pad supported beneath the garment and adapted to withstand the pressure of the pressing iron against the upper surface of the pressing cloth.

4. In a pressing pad, an elongated stuffed compressible body of relatively greater area in plan than in cross-section and providing a pressing pad, means secured to said body underlying the lower surface thereof for receiving the hand for supporting the pad and a flexible strip of single ply fabric secured at one end thereof to said body adjacent the hand receiving means and said flexible strip of single ply fabric providing a pressing cloth of a length and width to extend longitudinally and transversely over the upper surface thereof and to project outwardly beyond the opposite sides and one end thereof for overlying and protecting the surface of a garment during the pressing operation with the pad supported beneath the garment and adapted to withstand the pressure of the pressing iron against the upper surface of the pressing cloth.

5. In a pressing pad, a stuffed compressible body including an elongated forward portion of relatively greater width than thickness adapted to be disposed under the shoulder portion of a garment and an elongated extremity secured to one end of the forward portion and adapted to engage in and substantially throughout the sleeve of the garment, means secured to said body underlying the forward portion thereof for receiv-

ing the hand of the operator for supporting the said forward portion of the body and a flexible strip of single ply fabric secured to said forward portion of the body forwardly of the hand receiving means and providing a pressing cloth of a length and width to extend longitudinally and transversely over the upper surface of the body and to project outwardly beyond the opposite sides and one end thereof for overlying and protecting the surface of a garment during the pressing operation with the pad supported beneath the garment and adapted to withstand the pressure of the pressing iron against the upper surface of the pressing cloth.
